DESIGN FOR AN AUTOMOBILE HEATER

Raymond Loewy, New York, N. Y., assignor to Tropic-Aire, Incorporated, Minneapolis, Minn., a corporation of Delaware

Application August 16, 1937, Serial No. 71,128

Term of patent 3½ years

To all whom it may concern:

Be it known that I, Raymond Loewy, a citizen of France, residing at New York, in the county of New York and State of New York, have invented a new, original, and ornamental Design for an Automobile Heater, of which the following is a specification, reference being had to the accompanying drawing, forming part thereof, and in which

I claim:

The ornamental design for an automobile heater, substantially as shown.

RAYMOND LOEWY.
